United States Patent Office

Des. 218,860
Patented Sept. 29, 1970

218,860

CANDLE

Martha A. Madden, 1604 Shannon St.,
Monroe, La. 71201

Filed May 22, 1969, Ser. No. 17,366

Term of patent 14 years

Int. Cl. D26—05

U.S. Cl. D73—1

FIG. 1 is a front and left side perspective view of a candle showing my new design;

FIG. 2 is a front elevational view; and

FIG. 3 is a left side elevational view thereof.

I claim:

The ornamental design for a candle, substantially as shown:
